S. GANGMARK

BUILDING BLOCK

Filed Aug. 7, 1926

UNITED STATES PATENT OFFICE.

SEVERIN GANGMARK, OF SEATTLE, WASHINGTON.

BUILDING BLOCK.

Application filed August 7, 1926. Serial No. 127,790.

This invention relates to concrete building-blocks; and its object, generally, is the provision of a block of this character which may be readily laid to afford a strong, durable moisture proof wall. More specific objects and advantages of the invention will appear in the following description.

The invention is illustrated in the accompanying drawing, wherein,—

10 Figure 1 is a perspective view of my improved building block; Fig. 2 is a transverse vertical section of Fig. 1; Fig. 3 is a perspective view of the slab spacing and reinforcing assembly such as employed in the 15 completed block shown in Fig. 1; Fig. 4 is a detail horizontal section to a larger scale of portions of two blocks to illustrate the manner of bonding the same; Fig. 5 is a view, partly in front elevation and partly in section, of a portion of a building wall embodying my improved blocks; and Fig. 6 is 20 a plan view of Fig. 5, including part of a window casing shown in horizontal section.

According to the present invention a 25 building block is composed of two thin rectangular slabs 10 held in parallel spaced apart relation by means of transversely arranged bridge plates 11. The two slabs of a block are each formed to provide at its 30 top a longitudinal tongue 12 protruding above horizontal shoulders 13; and in its lower edge a longitudinal groove 14 to receive the tongue of a block of a wall course next below.

35 Each end of a block is formed to provide a vertical groove 15 to receive mortar or other suitable plastic material as represented by 16 in Figs. 4 and 6.

The above referred to bridge plates 11, 40 made of wood or other suitable material, are of less height than that of the associated slabs 10 and have their ends embedded in the latter. Said bridge plates are located, preferably, at about midheight of the associated 45 slabs 10 of a block to afford spaces above and below the plates to accommodate horizontal timbers, such as 17 in Figs. 5 and 6 for example, said timbers being nailed or otherwise secured to the bridge plates and 50 thus serve as reinforcing members of a wall.

The bridge plates, moreover, are each disposed to have its outer surface 18 in a plane, or nearly so, with the plane of the respective ends of the companion slabs 10 of a 55 block, the grooves 15 in the latter being continued as at 15¹ through the bridge plates.

As shown in Fig. 3 the companion bridge plates 11 of a block are connected with each other by reinforcing rods 19 having hooked or looped ends, as 20, in engaging relation 60 with anchor devices such as metal bars 21, nails or the like, which, in turn, engage in the plates. The rods 19 and the metal connections 21 of the plates are all embedded within the respective block slabs, and the 65 material of the latter serves with the bridge plates to afford a monolithic block of great strength and durability.

In the making of a block, the plastic concrete is cast about a skeleton structure (Fig. 70 3) in a mold. The surface of the slab member which is to be exposed may be finished in any desired manner.

An attractive finish is had by means of an outer layer 22 (Fig. 2) of suitably colored cement into which is pressed pieces of broken rock, glass or other substance which will produce a desired artistic or architectural effect.

In constructing a wall, the blocks of the 80 inner and outer slab tiers are laid with lime or cement mortar, the planes of the joints between the blocks of each course being disposed, preferably, intermediate the planes of the joints of a course next below. The 85 blocks of a course may be secured together by nails or bolts (not shown) engaging the bridge plates of adjacent blocks. A wall composed of blocks as hereinbefore described, being hollow provides an air 90 circulating chamber, across which the bridge plates extend to couple the inner and outer concrete slab elements, thus forming a 95 strong wall, which will be economical in the use of concrete, of relatively light weight and which will be practically damp proof.

What I claim, is,—

1. A building-block comprising two spaced apart concrete slab sections, wooden bridge plates having their ends embedded in the 100 respective sections to receive fastenings for securing the adjacent blocks of a course thereof together, the outer surface of a plate being in a plane with the outer extremity of the slab sections at each end of 105 the block, grooves provided in the ends of the slab sections and extending across the respective plates, and tongues and grooves provided along the upper and lower longitudinal edges of the respective slabs.

2. In a building-block comprising two spaced apart concrete slab sections, bridge

- plates having their ends embedded in the slab sections, said plates being provided with recesses arranged to cooperate with the recesses of the plate of adjacent blocks to 5 accommodate a bonding material for securing said blocks in longitudinal alignment with each other and reinforcing means embedded in said slabs and having their ends connected to the respective plates.
- 10 3. In a building-block having two concrete slab sections, a bridge plate embedded in the concrete at each end of the block for retaining the slabs in parallel spaced apart relation, rods extending above and below each 15 of the embedded portions of the plates, and longitudinally disposed reinforcing means provided within the slabs between said rods above and below the plates respectively of each slab.
- 15 4. In a building block, two concrete slabs, a rectangular bridge plate of less depth than the slabs having its ends embedded in the slabs at each end of the block, and reinforcing 20 means coupling said bridge plates in longitudinally spaced apart relation within each slab.
5. In a building block having two concrete slab members, plate members retaining the slab members in horizontally spaced apart relation to afford inner and outer surfaces 30 of a wall, means extending longitudinally of the block in each of said slabs and cooperating with the embedded portions of the plate members at both ends of the respective slabs for reinforcing the latter, the slab for the outer wall-surface having pieces of rocks 35 partially embedded therein.
6. In a building-wall, in combination, a horizontal course of concrete slabs each containing horizontally and vertically arranged 40 reinforcing elements, said slabs being provided in the ends thereof with vertically disposed grooves, and means interposed between the successive slabs and engaging in the grooves thereof for uniting the slabs. 45

Signed at Seattle, Washington, this 12th day of June 1926.

SEVERIN GANGMARK.
